W. J. BAILEY.

SIGNALING AND TELEPHONE SYSTEM FOR RAILROADS.

APPLICATION FILED DEC. 18, 1912.

1,073,018.

Patented Sept. 9, 1913.

UNITED STATES PATENT OFFICE.

WARDER J. BAILEY, OF CEDARVILLE, WEST VIRGINIA.

SIGNALING AND TELEPHONE SYSTEM FOR RAILROADS.

1,073,018.

Specification of Letters Patent.

Patented Sept. 9, 1913.

Application filed December 18, 1912. Serial No. 737,469.

To all whom it may concern:

Be it known that I, WARDER J. BAILEY, a citizen of the United States of America, residing at Cedarville, in the county of Gilmer and State of West Virginia, have invented new and useful Improvements in Signaling and Telephone Systems for Railroads, of which the following is a specification.

10 This invention relates to improvements in signaling and telephone systems for use on railroads and has particular application to systems of this type whereby trains approaching each other will cause the operation of signals to notify the engineers in charge of such trains of the condition of the track ahead and whereby the engineer of a train may have telephonic communication with the engineer of another train 15 within the same block and with the dispatcher's office or station master.

In carrying out the present invention, it is my purpose to provide a signaling and telephone system for railways in which 20 each train will be equipped with a telephone set which will be automatically connected in circuit with the telephone set at each station as the train approaches within a certain distance thereof, and whereby the 25 telephone set on a train at a remote distance from the station may be connected in circuit with the telephone set at a station, and whereby the telephone sets on two approaching trains will be automatically connected in circuit when the trains are in 30 dangerous proximity or in the same block, the connecting of the telephone sets in circuit affecting the energizing of signals to indicate the approach of a train to a station or the approach of one train to another so that telephonic communication may be established.

It is also my purpose to provide a system of the character above set forth which 45 will embrace the desired features of simplicity, efficiency, durability and reliability coupled with cheapness of cost in installation and which when once installed may be maintained at a minimum expense.

50 Furthermore, I aim to provide a signal and telephone system by means of which communication may be established between a station and a train approaching within a given or predetermined zone from the station by means of a metallic return circuit, or between the station and a train at a con-

siderable distance through a ground return circuit, the engineer of the train establishing a ground connection with his telephone set by projecting a weighted spear or 60 other metallic object upon or into the ground.

With the above and other objects in view, the invention consists in the construction, combination and arrangement of parts hereinafter set forth in and falling within the 65 scope of the claims.

In the accompanying drawing the figure is a diagrammatic view of a section of track showing the telephone set at one station and 70 on three trains.

Referring now to the drawing in detail, the numerals 1 and 2 designate the rails of a track, while 3 and 3' indicate the sections of a stationary main conductor or third rail extending along the track and suitably insulated or spaced apart from the rails thereof, the contiguous ends of adjacent sections being overlapped, as at 4, so that two trains in adjacent blocks will signal each 80 other in time to avoid an accident, when such trains are proceeding in opposite directions.

Each station, as A, is equipped with a telephone set B of any well known or preferred construction, one terminal of the set being connected by a wire 5 to the conductor 3, and the other terminal by way of a wire 6, with the track rail 2. Also at each station is a bell 7 independent of the bell of 90 the telephone set and having one terminal connected by a wire 8 with the rail 2 and the other terminal connected through the medium of a wire 9 to the earth as at 10. A suitable form of switch 11 is arranged in the wire 9 so that the ground connection to the bell 7 may be opened and the terminal 12 of the telephone set connected to the ground.

The trains T, T', and T'' are each illustrated diagrammatically by an axle and a pair of wheels bearing on the track rails 1 and 2. Each train carries a telephone set and a partial circuit therefor including a wire 13 connected to one terminal, as 14, of the telephone set and having its free end terminating in a wheel, brush, shoe or the like 15 mounted on the locomotive in such manner as to ride on the sectional third rail extending along the track, and a wire 16 connected to the other terminal of the telephone set, as 14', and having the free end

thereof connected in a suitable manner with the axle 17 so as to connect the telephone set to the track rail 1. Each telephone set includes a receiver 18, a forked switch 19, 5 a transformer 20, the primary winding of which is connected in circuit with the transmitter 21 and a battery 22, a ringer 23 and a continuously rotating magneto 24 suitably driven and connected by a wire 25 with the terminal 14. Each train telephone set is also equipped with means for obtaining a ground connection, such means, in the present instance, being in the form of a spear 26 connected by a flexible cord conductor 27 with the terminal 14, so that the engineer may toss or throw the spear from the cab into the road bed to ground the said terminal of the telephone set.

When a train, as for example, train T, is 20 in such proximity to the station A that the contact wheel 15 of the train engages the respective conductor of the third rail section 3, a circuit will be closed including the telephone sets of train T and of the station. Since the generator 24 is continuously 25 rotated, current will flow through the path indicated by the arrows *a*, such path consisting of the wire 25, terminal 14, wire 13, conductor 3, wire 5, bell of the telephone B, 30 wire 6, rail 1, axle 17 of train T, wires 16 and 16', receiver hook 19, bell 23, and generator 24. The engineer of train T and the station master in charge of station A will thus be notified that telephonic 35 communication may be had between the train and station for the exchange of orders or any other purpose. It will be noted that no use has been made of the grounding 26 of train T, as this is unnecessary because the circuit 40 includes the section 3 of the third rail and is connected with the station of the telephone sets. When, however, the train is at point remote from the station, as for instance, train T' and the engineer desires to 45 establish communication between his telephone set and the station set, the grounding device is projected into the ground. The main conductor or third rail is now cut out of the circuit and current flows through the 50 path indicated by *b*, this path consisting of the generator 24, wire 25, flexible conductor 27, grounding device 26, earth, wire 9, call bell 7, wire 8, track rail 1, axle 17 of the train T', wires 16, and 16', receiver fork 55 19, bell 23 and generator 24. The station master, upon hearing the ringing of the bell 7, manipulates the switch 11 so as to connect his telephone set in circuit by throwing the switch to the dotted line position. This 60 talking circuit is practically the same as the ringing circuit except that the telephone B takes the place of the call bell 7.

In order to prevent trains which may be simultaneously running on the track in 65 the same direction from signaling each

other, a pole changer 28 is connected in the circuit of each magneto 24, between such magneto and the bell 23 and wire 25; and these pole changers are so arranged that the like poles of their sources of energy are 70 connected to the main conductor or third rail and to the track or return conductor, respectively, and when thus arranged the electric currents will oppose one another and consequently prevent the energization of the 75 signals in the engines, when such engines or trains are proceeding in the same direction. On the contrary, trains running or operating on the track in opposite directions have their signaling apparatus connected to 80 the conductors in reverse polarity, that is, to say, in series, and when thus arranged no two trains proceeding in opposite directions or toward each other can be on the same block or section without signaling each 85 other.

Let it now be assumed that trains T¹ and T² are approaching each other and are within the danger zone. In this condition of the system, the magnetos 24, 24 of the two trains 90 will be connected in series with each other with the effect to energize the bells 23, 23 in each engine cab and so warn the engineers in charge of the trains of the condition of the track ahead, the circuit or path traversed by the current consisting of the generator 24 on the train T¹, bell 23, switch 19, wire 16' and wire 16, axle and wheels 17, the portion of the track rail 1 between the trains, axle and wheels 17 of train T², wires 100 16 and 16', switch 19, bell 23, generator 24, wire 25, wire 13, section 3' of the main conductor or third rail and wires 13 and 25 of the train T¹ and the other side of the generator on the last-mentioned train. Thus, 105 the bells 23, 23 of the trains are energized.

From the foregoing description taken in connection with the diagram illustrated in the accompanying drawing, the construction and mode of operation of my invention will 110 be readily apparent. It will be seen that I have provided a railway signaling and telephone system wherein each telephone set employed is equipped with a partial circuit, such circuits being rendered complete or connected to one another by way of a main conductor or third rail and one of the rails of the track way, when such telephone sets are brought within a predetermined or prescribed zone, and wherein the partial circuits 115 may be connected to one another when beyond the prescribed distance and independently of the main conductor or third rail.

While I have herein shown and described 125 one particular embodiment of my invention by way of illustration, I wish it to be understood that I do not confine myself to all the precise details of construction herein described and delineated, as modification and 130

variation may be made within the scope of the claims and without departing from the spirit of the invention.

I claim:

- 5 1. In a railway signaling system, the combination with the track rails and a main conductor, of a station telephone set, a partial circuit therefor including said main conductor and one of the track rails, a station signal independent of the telephone set, a circuit for such signal including one of the track rails and a ground connection, a train carried telephone set, a partial circuit therefor forming with the first-mentioned 10 partial circuit a complete circuit for both telephone sets when the train is within a predetermined distance of the station, and means for establishing a complete circuit 15 between the train carried telephone set and the station signal independently of the station telephone set.
- 20 2. In a railway signaling system, the combination with the track rails and a main conductor, of a station telephone set, a partial circuit therefor including said main conductor and one of the track rails, a station signal independent of the telephone set, a circuit for such signal including one of the track rails and a ground connection, a train carried telephone set, a partial circuit therefor forming with the first-mentioned partial circuit a complete circuit for both telephone sets when the train is within a predetermined 25 distance of the station, means for establishing a ground connection for the train carried telephone set to energize said station signal, and means for establishing a complete circuit composed of said partial circuits independently of said main conductor and for cutting out said station signal.

mined distance of the station, means for establishing a ground connection for the train 35 carried telephone set to energize said station signal, and means for establishing a complete circuit composed of said partial circuit independently of said main conductor and when the train is beyond the prescribed 40 distance from the station.

3. In a railway signaling system, the combination with the track rails and a main conductor, of a station telephone set, a partial circuit therefor including a main conductor 45 and one of the track rails, a station signal independent of the telephone set, a circuit for such signal including one of the track rails and a ground connection, a train carried telephone set, a partial circuit therefor 50 forming with the first-mentioned partial circuit a complete circuit for both telephone sets when the train is within a predetermined distance of the station, means for establishing a ground connection for the train 55 carried telephone set to energize said station signal, and means for establishing a complete circuit composed of said partial circuits independently of said main conductor and for cutting out said station signal. 60

In testimony whereof I affix my signature in presence of two witnesses.

WARDER J. BAILEY.
